UNITED STATES PATENT OFFICE.

WARDER J. BAILEY AND JAMES M. ROBINSON, OF COPEN, WEST VIRGINIA.

DERAILMENT-BRAKE-APPLYING MECHANISM.

1,320,195.

Specification of Letters Patent.

Patented Oct. 28, 1919.

Application filed June 17, 1919. Serial No. 304,821.

To all whom it may concern:

Be it known that we, WARDER J. BAILEY and JAMES M. ROBINSON, citizens of the United States, residing at Copen, in the county of Braxton and State of West Virginia, have invented new and useful Improvements in Derailment-Brake-Applying Mechanism, of which the following is a specification.

10 This invention relates to improvements in railway safety devices, and aims to provide means for automatically setting the brakes of an air brake system, in the event of any one or more of the car trucks leaving the rail.

Broadly stated, the invention contemplates means carried by the car for contact with the road bed, in the event of the wheels leaving the rails, said means acting to open 20 the train line and exhaust the air to set the brakes for the entire train.

The invention therefore consists of the following described method, the details of construction to be hereinafter described being 25 for purposes of illustration, as this structure may be varied without departing from the spirit or sacrificing any of the advantages of the invention.

In the drawings:—

30 Figure 1 is a fragmentary cross sectional view showing the invention applied to the truck of a railway car.

Fig. 2 is a top plan view showing the manner of connection with the angle cock of 35 the train line.

Fig. 3 is a longitudinal sectional view.

Fig. 4 is an enlarged elevation of the contact member or shoe.

Fig. 5 is a sectional view on the line 5—5 40 of Fig. 4.

Referring to the drawings in detail, the invention which is designed to be applied to the pony trucks of a railway car, includes a rock shaft 10, the latter being mounted in 45 bearings 11 which are secured to the bottom stay of the pony arches. This shaft is provided at each end with crank arms 12, upon which are mounted contact members 13 designed for engagement with the surface of the road bed in the event of the wheel of the truck leaving the rail.

The contact members 13, each include a shoe 14 which is supported from crank arms 12 through the medium of hangers 15, 50 the latter being provided with eyes 16 to pro-

vide a pivotal movement for the shoe upon the crank arm. In order to hold the contact member 13 normally in a vertical position, a flat spring 17 is secured to each side of the shoe 14 and has its free upper end in 60 contacting engagement with a wedge 18 rigidly secured to the crank arm 12. The length of the member 13 is such that when the wheels of the truck are upon the rails, the shoe 14 is disposed above and out of contact with the roadway, but should the wheels leave the rails the shoe will act to rock the shaft 12. By securing the contact member 13 in the manner shown, injury thereto is prevented through its oscillating or pivotal 65 movement, which will occur when the shoe strikes an obstruction.

Extending laterally from the rock shaft 10, is an arm 19, one end of which is adjustably connected with vertically disposed 70 rods 20. The end of the rod 20 is adjustably connected with the arm 19 and the opposite end of this rod is pivoted to the ratchet handle 21 of an angle cock 22 of the train line. The connection between the rod 20 75 and the handle 21 is such that when the shaft 10 is rocked, the rod 20 will be moved to operate the handle 21 and open the cock 22, while a spring 23 engaging the arm 19 will return said rod and shaft 10 to its original 80 or normal position, the handle 21 of the angle cock 22 will remain in open position until manually closed.

In practice one of these devices is applied to each of the trucks, so that if the wheels 90 of any trucks on the train leaves the rails, the contact member 13 will operate to open the angle cock and apply the brakes of the entire train.

The invention is susceptible of various 95 changes in its form, proportions and minor details of construction and the right is herein reserved to make such changes as will properly fall within the scope of the appended claims.

We claim:—

1. The combination with an air brake system for railway cars, of a rock shaft positioned transversely across said cars, a crank at each end of said shaft, a contact member pivotally connected to each of said cranks and normally disposed above the surface of the road bed when the wheels are on the rails and adapted to contact with the road bed when the wheels leave the rails and 110

- operate the rock shaft and means connecting the rock shaft with a valve in the train line for operating the latter to apply the brakes.
2. The combination with an air brake system for railway cars, of a rock shaft positioned transversely across said cars, a crank at each end of said shaft, a contact member pivotally connected to each of said cranks and normally disposed above the surface of the road bed when the wheels are on the rails and adapted to contact with the road bed when the wheels leave the rails and operate said rock shaft, means for connecting the contact members to the rock shaft to permit of a yielding rotary movement and means connecting the rock shaft and a valve in the train line for operating the latter to apply the brakes.
3. In combination with an air brake system for railway cars, of a rock shaft positioned transversely across said cars, a crank at the end of said shaft, a contact member pivotally connected to each of said cranks and normally disposed above the surface of the road bed when the wheels are on the rails and adapted to contact with the road bed when the wheels leave the rails and operate said rock shaft, spaced parallel springs

carried by the contact member and disposed upon each side of the pivotal connection to permit of the yielding rotary movement and means connecting the rock shaft with a valve in the train line, whereby the latter will be opened upon operation of said rock shaft and remain in such open position.

4. In combination with an air brake system for railway cars, the rock shaft positioned transversely across said cars, a crank at each end of said shaft, a contact member pivotally connected to each of said cranks and normally disposed above the surface of the road bed when the wheels are on the rails and adapted to contact with the road bed when the wheels leave the rails and operate the rock shaft, means for connecting said contact member to the shaft to permit of the yielding rotary movement and means including a longitudinally movable rod connecting the rock shaft with a valve in the train line, whereby the latter will be opened upon operation of said rock shaft and remain in such open position.

In testimony whereof we affix our signatures.

WARDER J. BAILEY.
JAMES M. ROBINSON.
